his attorney

UNITED STATES PATENT OFFICE.

CHARLES J. KELLOWAY, OF WILMINGTON, NORTH CAROLINA, ASSIGNOR TO THE UNION SWITCH & SIGNAL COMPANY, OF SWISSEVALE, PENNSYLVANIA, A CORPORATION OF PENNSYLVANIA.

RAILWAY SIGNALING.

Application filed September 24, 1926. Serial No. 137,480.

My invention relates to railway signaling, and particularly to signaling of the automatic block type involving track circuits.

In the usual systems of this character, if a signal should stick in the proceed position or for any other reason should fail to assume its stop position when the associated block is occupied, the signal next in the rear will fail to indicate caution as it should. One feature of my invention is the provision of means operating, if a signal fails to assume its stop position when a train enters the associated block, to cause the signal next in the rear to assume its stop position.

The accompanying drawing is a diagrammatic view showing one form of apparatus embodying my invention.

Referring to the drawing, the reference characters 1 and 1^a designate the track rails of a railway along which traffic normally moves in the direction indicated by the arrow. These rails are divided by insulated joints 2 to form successive blocks or sections, of which only one complete section J—K is shown in the drawing. Each section is provided with the usual track circuit, comprising a battery B connected across the rails at the exit end of the section through a limiting resistance 5 and a pole-changer PC, as well as a track relay J connected across the rails at the entrance end of the section and responsive to reversals of the position of the pole-changer PC. Located at the entrance end of each section is a signal designated by the reference character S with an exponent corresponding to the location, each of which signals is controlled by the associated track relay T in such manner that the signal indicates proceed when the relay is energized in the normal direction, caution when the relay is energized in the reverse direction, and stop when the relay is de-energized. The control of each signal is effected in the usual manner by a neutral contact 3 and a polar contact 4 in the associated relay. Each pole-changer PC is operated by the associated signal S in such manner that this pole-changer is in the normal position when the signal indicates proceed or caution, and in the reverse position when the signal indicates stop.

The parts of the apparatus thus far described are the usual parts in a polarized

track circuit automatic signaling system, and consequently no detailed explanation of the operation of these parts is required.

Each signal S operates a circuit controller C in such manner that the circuit controller is closed when the signal is in the proceed position but not when the signal is in the stop position. Preferably, this circuit controller is closed from the 88° position of the signal to its 90° or proceed position, although this particular range is not essential to my invention.

Each track section is provided with a shunting path of low resistance which passes from rail 1^a, through wire 8, circuit controller C, wire 9, resistance 11, wire 12, back contact 7 of the track relay for the next section in advance, and wire 10 to track rail 1. It will be seen that this shunt is closed only when the track relay is open and the signal is in or near its proceed position. Resistance 11 preferably has a value of substantially 0.2 ohm.

I will now assume that a train enters the section to the right of point K and that signal S^K is mechanically stuck in its proceed position, or that for some other reason this signal fails to move to the stop position as it should. Track relay T^K will open, and since circuit controller C^K is now closed, the track circuit for section J—K is shunted by the path of low resistance through C^K and 7, thereby deenergizing track relay T^J and placing signal S^J at stop. This shunting of the track circuit is analogous to that produced by the presence of a train and does not injuriously affect battery B, because of the limiting resistance 5 and resistance 11. It will be noted that this auxiliary shunting of a track circuit occurs each time a train enters the block next in advance, but if the signals are working in proper manner, the auxiliary shunt exists only during the time required for the circuit controller C to open. This circuit controller may be arranged to open immediately after the signal moves away from its full proceed position, on the assumption that the signal having once started, may be assumed to move all the way to its stop position.

Although I have herein shown and described only one form of railway signaling apparatus embodying my invention, it is

understood that various changes and modifications may be made therein within the scope of the appended claims without departing from the spirit and scope of my invention.

5 Having thus described my invention, what I claim is:

1. In combination, a railway track divided into sections, a track circuit for each section including a track relay, a signal

10 for each section controlled by the relay for such section, and means for shunting the track circuit for each section if the section next in advance is occupied and the signal for the latter section is in the proceed position.

15 2. In combination, a railway track divided into sections, a track circuit for each section including a track relay, a signal for each section controlled by the relay for such

20 section, a circuit controller for each signal arranged to be closed when the signal is in the proceed position and open when the signal is in the stop position, and a path of low resistance for shunting the track 25 circuit for each section including in series a back contact of the track relay for the section next in advance and the circuit controller for the signal of such section next in advance.

30 3. In a signal system for railroads having tracks divided into sections each provided with a polarized track relay, a semaphore signal for each section, a pole-changer operated by each signal and controlling the po-

35 larity of the track circuit for the section next in the rear, and means for shunting the track circuit of each section if the next sec-

tion in advance is occupied and the signal thereof is in the proceed position.

4. In a signal system for railroads, having 40 tracks divided into sections each provided with a polarized track relay, a semaphore signal for each section, a pole-changer operated by each signal and controlling the polarity of the track circuit for the section 45 next in the rear, a circuit breaker operated by each signal and closed in its proceed position, and a partial circuit for shunting the track circuit of each section including in series a back contact of the track relay 50 of the section next in advance and the circuit breaker of the signal for that section.

5. A signal system for railroads having tracks divided into sections, comprising a semaphore signal for each section, a polarized 55 track relay for each section governing indications of the signal for that section, a track battery and limiting resistance for supplying current to each track relay, a pole-changer operated by each signal for reversing the polarity of the connections between the track battery and the track relay of the section next in the rear, a circuit breaker operated by each signal and closed in its proceed position, and a partial circuit of 60 low resistance connected across the track rails of each section for shunting its track relay and including in series the back contact of the track relay of the next section in advance and the circuit breaker of the signal 65 for said next section in advance.

In testimony whereof I affix my signature.

CHARLES J. KELLOWAY.
